UNITED STATES PATENT OFFICE.

GEORGE ALBERT LYON, OF PHILADELPHIA, PENNSYLVANIA.

AUTOMOBILE-BUFFER.

1,325,736.

Specification of Letters Patent. Patented Dec. 23, 1919.

Application filed April 11, 1918. Serial No. 227,866.

To all whom it may concern:

Be it known that I, GEORGE ALBERT LYON, a citizen of the United States, and resident of Philadelphia, Philadelphia county, State 5 of Pennsylvania, have made a certain new and useful Invention Relating to Automobile-Buffers, of which the following is a specification, taken in connection with the accompanying drawing, which forms part 10 of the same.

This invention relates especially to resili- 15 ent or spring strip buffers for use on Ford or similar automobiles or other vehicles in which the rearwardly extending attaching 20 members are oppositely inclined or bent into reinforcing diagonal position, so that they are considerably stiffened against lateral vibration without losing their vertical ri- 25 gidity to an undesirable extent. These at- 30 taching members may have rearward anchoring extensions formed integral therewith so as to extend a considerable distance backward along the frame members to which they may be bolted or secured as by 35 bolting an inturned end of such an anchor- 40 ing extension to the frame where the usual drip pan bolt is located. These diagonal attaching members are not only stiffer and stronger against lateral vibration and colli- 45 sion impact, but they may, if desired, be clamped substantially flat against the inclined lamp brackets so as to give a rigid and strong attachment for the buffer mem- 50 bers. These attaching members may have 55 forwardly and outwardly curved portions at their front ends which may be bolted or otherwise connected to the front or impact receiving members of the buffer which may be forwardly bowed in substantially uni- 60 formly curved shape, if desired, and these impact receiving members may overlap and reinforce each other adjacent the middle of 65 the buffer and be bolted or otherwise connected at these portions.

45 In the accompanying drawing showing in a somewhat diagrammatic way illustrative embodiments of the invention,

Figure 1 is a perspective view showing the buffer attached to a Ford automobile, 50 parts of which are shown in dotted lines.

Fig. 2 is an enlarged transverse section taken substantially along the line 2--2 of Fig. 1.

Fig. 3 is a plan view of the buffer; and

55 Fig. 4 shows the buffer when disconnected and arranged for shipping.

The front or impact receiving member of the buffer may be of any suitable form and construction and it may be advantageously formed of a plurality of overlapping spring 60 strips, such as 19, 20, which may as indicated in Fig. 3 be forwardly bowed and have substantially uniform curvature so as to give a pleasing appearance to the finished buffer and allow lateral adjustment of these 65 impact receiving members when it is desired to have a buffer of adjustable width to fit different width vehicle frames. Any suitable connecting means may be used to connect these front members preferably in 70 a vertically rigid manner. For a Ford automobile buffer connector bolts, such as 22, may be conveniently used which may have a convex or boss-shaped head in the front of the buffer member and extend through 75 holes or connecting apertures, such as 23, in the spring strips 19, 20. If desired, the bolts may be formed with polygonal or other non-circular shanks, such as 21, to fit within corresponding holes in one or both of the 80 spring strips which are tightly connected as by screwing home the nuts 24 on these bolts.

The spring strip attaching members 5, 6 may have forwardly and outwardly curved portions terminating in the ends 7, 8 which 85 are arranged substantially parallel to the adjacent portions of the impact receiving members and securely clamped or connected thereto by any suitable connectors. U-bolt connectors such as 16, are desirable for 90 this purpose and as indicated may extend through suitable holes 26 in the coöperating members so as not only to frictionally hold them together but to maintain them in substantial vertical alinement when the nuts 18 95 on the bolt shanks are screwed down on the lock washers 17, for example. In order to secure greater lateral rigidity in these attaching members they may with advantage have their rearwardly extending portions 100 oppositely vertically inclined or bent about their axes into diagonal position so as to mutually reinforce and stiffen this part of the buffer against lateral vibration or yielding, while at the same time sufficient vertical 105 rigidity is retained in these spring strips so that they are not undesirably weakened against vertical running vibration. This desirable form of oppositely inclined stiffening attaching members is disclosed and claimed 110 more broadly in my copending application, Serial No. 236,513, filed May 25, 1918. It

is desirable to have the front ends of these attaching members substantially vertical adjacent the impact receiving portions of the buffer and from this point the inclination 5 may gradually increase as shown in Fig. 3 until the substantially straight rearwardly extending part of these attaching members is reached which may be oppositely inclined at about 45 degrees or so from the vertical 10 as indicated in Fig. 2.

In some cases these attaching members may be extended to a greater or less degree to form anchoring extensions which may be conveniently bolted directly to the vehicle 15 frame at a considerable distance back of the radiator or front portion in some instances. With the ordinary Ford automobile the frame members 4 are substantially straight up to about the front of the hood 1 as indicated in Fig. 1, and the drip pan 28 is usually bolted to the bottom flange of each of these frame members by suitable bolts, such as 12, passing therethrough, see Fig. 2. The lamp brackets 2, 3, bolted to and 20 extending diagonally out from the frame members adjacent the front of the machine make it difficult to attach a bumper to the frame without special fittings or connections, but this oppositely inclined diagonal arrangement 25 of the attaching members may be utilized to have such oppositely inclined attaching members lie against and if desired be clamped to these inclined lamp brackets near the frame members. For this purpose one 30 or more U-bolt attaching clamps, such as 14, may be used adjacent each lamp bracket, and if desired extend through holes punched or otherwise formed in the attaching members 5, 6, so that the nuts 15 together with 35 the lock washers 25, if desired, tightly hold these parts together. The anchoring extensions may be formed with the inturned ends 9, 10 having holes through which extend the usual or special pan bolts 12 having, if desired, nuts 11 on the inside of the frame 40 flange. In this way the anchoring extensions are firmly and strongly secured to the frame and the U-bolt attaching clamps provide a rigid and strong connection for the buffer 45 members near the front of the automobile frame so that the free ends of the strips forming the impact receiving or front members of the buffer are rigidly and strongly held in protective position in front of the 50 automobile wheels. The use of U-bolt connectors and attaching clamps is advantageous in this connection because it furnishes a double security against loosening, the U-bolt still remaining in position if one of 55 the nuts has become loosened or even lost. The U-bolt attaching connector 16 is desirable for this reason and also because it stiffens and alines the two buffer members through which it passes and at the same 60 time gives a pleasing and finished appear- 65

ance to the buffer front as indicated in Fig. 1.

As previously indicated the buffer may be readily assembled and clamped to the automobile by practically any garage man or 70 car owner without special tools or instructions and the buffer is composed of such shaped and sized parts as make a compact shipping package, Fig. 4 indicating one form in which the members may be arranged 75 for this purpose. It is also evident that the buffer elements may be quickly and conveniently bent and fabricated and given the desired spring temper which imparts to them a maximum of strength and resilience 80 to take up a heavy collision impact and protect the automobile.

This invention has been described in connection with a number of elements, forms, proportions, parts, arrangements, materials, 85 methods of connection and use, to the details of which disclosure the invention is not of course to be limited, since what is claimed as new and what is desired to be secured by Letters Patent is set forth in the appended 90 claims.

I claim—

1. The automobile buffer adapted for use on Ford or similar automobiles and comprising a resilient front portion having connecting portions and outwardly extending free ends, coöperating spring strip attaching members having forwardly and outwardly extending portions and forward connecting portions to engage the adjacent ends 95 of the buffer front portion, attaching connectors to secure said attaching members to the front portion of the buffer, said attaching members having oppositely vertically inclined reinforcing diagonal portions to the rear of said curved portions and having integral anchoring extensions adapted to be bolted to the automobile frame members and U-bolt attaching clamps passing through 100 holes in said attaching members and adapted 105 to extend around the inclined lamp brackets of the automobile to clamp said attaching members against said lamp brackets.

2. The automobile buffer adapted for use on Ford or similar automobiles and comprising a resilient front portion having connecting portions and free ends, coöperating spring strip attaching members having forwardly and outwardly extending portions and forward connecting portions to engage the adjacent ends of the buffer front portion, attaching connectors to secure said attaching members to the front portion of the buffer, said attaching members having oppositely inclined reinforcing diagonal portions inclined at about 45° from the vertical 115 located to the rear of said curved portions and having integral anchoring extensions adapted to be bolted to the automobile and attaching clamps to clamp said attach- 120 125 130

ing members against the automobile lamp brackets.

3. The automobile buffer adapted for use on Ford or similar automobiles, and comprising an adjustable length resilient strip front member having connecting portions and free ends adapted to extend into protective position adjacent the automobile wheels, coöperating spring strip attaching members having forwardly and outwardly extending curved portions, and connecting portions adapted to engage and be detachably secured to the connecting portions of said front member, and attaching U-bolt connectors to secure said attaching members to said connecting portions of said front member, said attaching members having oppositely vertically inclined reinforcing diagonal portions to the rear of said curved portions and having integral anchoring extensions provided with inturned ends adapted to be secured beneath the automobile frame members and attaching clamps to secure said attaching members to the inclined lamp brackets of the automobile.

4. The automobile buffer adapted for use on Ford or similar automobiles, and comprising a front member having connecting portions and free ends, coöperating spring strip attaching members having forward curved portions, and connecting portions adapted to engage and be detachably secured to the connecting portions of said front member, said attaching members having oppositely vertically inclined reinforcing diagonal portions to the rear of said curved portions and having integral anchoring extensions provided with inturned ends adapted to be secured beneath the automobile frame members and attaching clamps to secure said attaching members to the inclined lamp brackets of the automobile.

5. The automobile buffer adapted for use on Ford or similar automobiles, and comprising a front member having connecting

portions and free ends, coöperating spring strip attaching members having forward curved portions, and connecting portions adapted to be secured to the connecting portions of said front member, said attaching members having oppositely vertically inclined reinforcing diagonal portions to the rear of said curved portions. 50

6. The automobile buffer adapted for use on Ford or other generally similar automobiles, and comprising relatively wide thin resilient strip and provided with free outwardly extending end portions, said buffer comprising a front member having connecting portions and resilient strip attaching members adapted to be connected to an automobile and to be detachably connected to said connecting portions of said front member, said attaching members having oppositely vertically inclined rear reinforcing diagonal portions to give increased lateral stiffness. 60

7. The automobile buffer adapted for use on Ford or other generally similar automobiles, and comprising resilient strip and provided with free outwardly extending end portions, said buffer comprising a front member having connecting portions and resilient strip attaching members adapted to be connected to said connecting portions of said front member, said attaching members having oppositely vertically inclined rear reinforcing diagonal portions to give increased lateral stiffness. 70

8. The automobile buffer adapted for use on Ford or other generally similar automobiles, and provided with free outwardly extending end portions, said buffer comprising a front member having connecting portions and resilient strip attaching members adapted to be connected to said connecting portions of said front member, said attaching members having oppositely vertically inclined reinforcing diagonal portions to give increased lateral stiffness. 80

GEORGE ALBERT LYON.
